(57)

CLAIM

The ornamental design for an interdental cleaner, as shown and described.

DESCRIPTION

- 1.1 is a perspective view;
 1.2 is a front view;
 1.3 is a back view;
 1.4 is a top view;
 1.5 is a bottom view;
 1.6 is a left view; and
 1.7 is a right view.
 2.1 is a perspective view;
 2.2 is a front view;
 2.3 is a back view;
 2.4 is a top view;
 2.5 is a bottom view;
 2.6 is a left view; and
 2.7 is a right view.
